UNITED STATES PATENT OFFICE.

HUBERT P. RICHARDS, OF NEW BRITAIN, CONNECTICUT.

PRESSER-FOOT FOR SEWING-MACHINES.

SPECIFICATION forming part of Letters Patent No. 601,280, dated March 29, 1898.

Application filed August 15, 1896. Serial No. 602,862. (No model.)

To all whom it may concern:

Be it known that I, HUBERT P. RICHARDS, a citizen of the United States, residing at New Britain, in the county of Hartford and State 5 of Connecticut, have invented certain new and useful Improvements in Presser-Feet for Sewing-Machines, of which the following is a specification.

My invention is a presser-foot for sewing machines; and the object thereof is the provision of a device of this character which will prevent the upward movement of the fabric (which is often of varying thickness) as it is fed beneath the same and which will also hold 15 the material firmly on the passage of the needle therethrough.

A further object of the invention is the provision of a presser-foot embodying a series of independent movable clamping or engaging 20 means whereby varying thicknesses of fabric can be simultaneously engaged and held against upward movement.

In the drawings accompanying and forming part of this specification, Figure 1 is a side 25 elevation of my improved presser-foot, representing in sectional view the throat-plate of a sewing-machine with a piece of work in position, said view also illustrating the position of the needle and in dotted lines a part 30 of a shuttle or loop-taker of ordinary form. Fig. 2 is a transverse sectional view of the same, taken in line *a a*, Fig. 1, and looking in the direction of the arrow. Fig. 3 is a plan view of the invention with the presser-bar in 35 section, taken in line *c c*, Fig. 1. Fig. 4 is a side view of another form of the invention; and Fig. 5 is a plan view, partly in section, thereof.

Similar characters designate like parts in all 40 the figures of the drawings.

In the use of the ordinary presser-foot it has been found in practice that when a piece of fabric of varying thickness is fed beneath the same it has no clamping action except on 45 that part of the work having the greatest thickness, hence causing the puckering of the portion of said fabric which the foot does not engage, and consequently resulting in the irregular feeding of the material. Furthermore, 50 in that class of machines in which it is necessary to form a loop of the thread and in which the fabric must remain immovable for

this purpose it has been found that not only is the loop frequently imperfectly made, but oftentimes is not formed at all, owing to the 55 fact that while the presser-foot is clamping the thick portion of the fabric or other material the thin part thereof is free for movement, and hence on the retraction of the needle the frictional engagement thereof with 60 the fabric is sufficient to carry the same upward, thus preventing the proper formation of a loop. In order to obviate this difficulty and disadvantage in sewing-machine presser-feet, I have provided an improved device of 65 this character which comprises, in a general way, a plurality of independently-acting yielding fabric-engaging means which are designated herein, respectively, as the "main" 70 clamping means, or "presser-foot" proper and the "supplemental" or "auxiliary" clamping means, whereby on the feeding of material of varying thickness the main clamping means will engage the thickest part thereof, while the supplemental clamping means will 75 bear against the thin part or parts of the fabric and thus prevent the upward movement of the same during the operation of the machine.

In the drawings the main clamping means 80 is designated generally by A and the supplemental clamping means by B, and said supplemental clamping means comprehends independently-acting yielding devices so combined and arranged with relation to the main 85 clamping means that the presser-foot in operation includes a plurality of independently-acting yielding means adapted to engage varying thicknesses of material and to clamp the same thoroughly on the throat-plate, whereby 90 upward movement of such material is positively prevented.

In constructing my presser-foot it is obvious and will be understood that the main clamping device or presser-foot proper may 95 be of any required form and that the supplemental clamping means may, in the broader feature of the invention, be secured thereto at opposite ends in any desired way and may be of a different construction than that illustrated, said main presser-foot being, as usual, spring-actuated in one direction in order to obtain a proper clamping action.

As the improved presser-foot may be used

with various forms of sewing-machines, so much only of an ordinary sewing-machine as is necessary to illustrate the working of the device is illustrated, and the features shown 5 comprise the usual throat-plate 5, having a needle-aperture 6 and provided with slots 7 for the dogs 8 of the feed mechanism, said slots forming throat-plate bars 7', a part of a rotatable loop-taker or shuttle 9 being also 10 represented by dotted lines in Figs. 1 and 2.

In the form of presser-foot shown in Figs. 1 to 3, inclusive, the main presser-foot 10, which in this instance is shown as a bifurcated foot having two parallel extending bars 15 12 and 13, forming a needle-opening 14, has each of said bars provided with a longitudinal recess 15, terminating at one end in a longitudinal slot 16, extending through the presser-foot and also terminating at its opposite 20 end in the furcated portion 17, having an offset or recess 18, and through which portion extends a pivot or stud 19, which may be removable or not, as desired.

A pair of springs 20 and 21, secured one at 25 each end of the presser-foot, are shown as having eyes at their rear ends through which the pivot or stud 19 is passed, and each spring is provided with a short downward extension 19', which engages the offset or shoulder 18 of 30 the main presser-foot and acts by its resiliency to hold the spring presser-foot in place. The shank of each of these springs is designated by 22 and is seated in a longitudinal recess 15 of the main presser-foot. At its free 35 end each spring is bowed or curved and extends downward through the slot 16 in the presser-foot. As will be obvious, the springs are mounted on the studs 19 at opposite ends of the presser-foot and project from said ends 40 in reverse directions toward each other, their bowed or convex portions passing through the slots 16 being preferably located in parallel planes. Each spring is preferably formed of wire, although, as is obvious, other material 45 may be employed if deemed advisable.

In the form of the invention shown in Figs. 4 and 5 the springs are secured in a position similar to that shown in the other figures, one, 23, being secured adjacent to the outer 50 end of the main presser-foot and the other, as 24, to the inner end of the same, said main presser-foot being provided with apertures 25 and 26 for the reception of the ends of said springs, whereby the fabric-engaging portions of the springs extend through slots 27 and beneath the presser-foot to thereby bear against and clamp the work. In this form of my invention the recesses 15 are omitted, and excepting the modification in the manner of 55 securing the springs in place the mode of operation of said springs is precisely the same as in the other views illustrated.

In the operation of the device when a thick part or seam of the fabric passes into position beneath both the supplemental clamping means B and the main clamping means or presser-foot proper, A, it is obvious, as shown in Fig. 1, that the supplemental clamping devices will act upon a thinner part of the fabric and prevent the same from upward movement until the seam or fold has passed beneath the device, thereby holding the fabric firmly in position on the throat-plate.

From the foregoing description it will be 75 seen that the fabric is at all times held firmly against the throat-plate and the feed-dogs adjacent to the path of the needle and that when the main presser-foot is in engagement with the thicker or seam part of the fabric 80 the supplemental clamping devices will always engage the relatively thin part, and thus hold the work in position firmly to permit the formation of the loop.

Having described my invention, I claim— 85

1. A presser - foot having supplemental clamping means secured thereto and comprising a pair of independent springs, one secured at the inner end and the other at the outer end of said foot, and each spring having a part thereof extending through said foot to engage work of varying thickness. 90

2. A presser-foot having a longitudinal recess at each end thereof terminating in a slot at or about the middle of said presser-foot, in 95 combination with springs, one secured at each end of the presser-foot and each having a straight portion or shank fitted in the longitudinal recess, and a convex or bowed portion at its free end working in the slot and 100 normally extending below the lower wall of the presser-foot.

3. A presser-foot having a bifurcated end, an offset or recess adjacent thereto, and a cross stud or pin, said foot also having a longitudinal slot; and a spring bent around said stud and having one end thereof in engagement with the wall of said offset or recess, and a part thereof extending through said 105 slot to engage work of varying thickness. 110

4. A presser-foot having a series of parallel slots and a series of independent yielding devices secured at the inner and outer ends of said presser-foot and at the upper side thereof, and each of said devices having a 115 part thereof curved to project through one of said slots, whereby said devices will be in position to engage work of varying thickness simultaneously with or independently of the presser-foot proper.

HUBERT P. RICHARDS.
